3 *George Waldemar Bungay* INVENTOR
Henry D. Williams BY ATTORNEY

UNITED STATES PATENT OFFICE.

GEORGE WALDEMAR BUNGAY, OF BROOKLYN, NEW YORK, ASSIGNOR TO ACME DIE
CASTING CORPORATION, A CORPORATION OF NEW YORK.

TRIP DEVICE.

Specification of Letters Patent. Patented Nov. 19, 1918.

1,285,020.

Application filed August 30, 1916. Serial No. 117,597.

To all whom it may concern:

Be it known that I, GEORGE WALDEMAR BUNGAY, a citizen of the United States, residing at the borough of Brooklyn, in the county of Kings and State of New York, have invented certain new and useful Improvements in Trip Devices, of which the following is a specification, reference being had therein to the accompanying drawings,

10 forming part thereof.

My present invention relates to an improved apparatus or means for applying the expansive power of an elastic fluid to the propulsion of a working element and especially to means for supplying molten metal to a suitable mold in die casting work and the like.

My invention is particularly suited to embodiment in the general type of apparatus disclosed and claimed in my co-pending application for patent Serial Number 54,123, filed October 5, 1915, which became Patent No. 1,279,249, September 17, 1918, for casting apparatus, and wherein the molten metal 25 is forced into the mold by the pressure of steam or other elastic fluid. I have therefore described and illustrated my improvement as embodied in the type of apparatus above mentioned, but it is to be understood 30 that my invention is not limited to the particular type of apparatus herein shown.

Where the molten metal is forced into the mold by means of a pump actuated by the expansive power of steam or the like as hitherto employed, the movement of the metal is relatively slow and the continuous pressure relatively low, owing to the time taken for the steam to enter the space above the driving piston, and the resistance offered 40 to entrance of steam into said space, whereby the full pressure in the boiler cannot make itself felt in the pump. In other words, this full pressure is constantly being lowered by the forward movement of the 45 piston. As a result, the molten metal as it enters the cold mold has a tendency to congeal against the walls thereof before the mold is filled and pressure applied, and thus 50 many cases.

It is the principal object of my present

improvement to produce a relatively sudden and, so to speak, explosive propulsion of the metal into the mold, whereby as I have discovered there is attained a greatly improved perfection in sharpness of detail in molding.

I find that this can be accomplished by causing the pressure to accumulate behind the driving piston of the pump while restraining the pump from forward movement, and finally suddenly removing the restraint. The pump moves forward under the sudden impact of the full pressure accumulated, and the filling of the mold is so suddenly accomplished that pressure can be exerted over the entire interior substantially 65 instantaneously and before the metal which touches the cold walls has time to congeal.

The means for carrying out this method 70 of operation lends itself to use in connection with apparatus wherein a high pressure of elastic fluid may be accumulated in positively active relation to a movable working element. I employ such means for the operation of a fluid controlled pump, and in so doing I restrain the pump temporarily to permit a body of steam or the like to accumulate behind the piston in "free relation" thereto, whereby I mean, unhampered 75 by the interference resulting from the resistance offered by entrance passages and conduits. In this manner I am enabled to make the driving piston start forward under the full pressure of the boiler. The 80 larger the space behind the driving piston, wherein accumulation of steam may take place, the more effectively can my invention be made available.

A preferred embodiment of my invention 85 is illustrated in the accompanying drawing wherein Figure 1 is a side elevation of the type of die casting machine described in my pending application aforesaid; Fig. 2 is a horizontal section on the line 2-2 in Fig. 1; and Fig. 3 is an end elevation of the machine shown in Fig. 1.

The details of the construction and operation of the machine as a whole are fully described in my aforesaid pending application, and I shall therefore give here only 90 a general description of a nature sufficient 100

as a foundation for the description of the improvement forming the subject matter of my present claims.

In the drawings the fire box is shown at 5 10, and within this box is placed the melting pot 11, containing the main body of molten metal. The pump for forcing this metal into the mold is shown in Fig. 2 at 12, the same being supported by a cross bar 13 or 10 other suitable means. The pump discharges into a pipe or duct 14 which curves upward from the bottom of the pump to a point slightly above the level of the molten metal, where a nozzle 15 is formed so as to fit 15 tightly into a suitable opening in the mold when this latter is closed and is forced down upon said nozzle.

The piston or plunger 16 of the pump is operated by a piston within the steam cylinder 17, with which it is connected by the rod 18, preferably made to fit within a socket 19 on the lower end of an upper rod section 20. This arrangement is merely to facilitate the assembling of the parts, and is not essential 25 to the invention. It is convenient, however, in providing the restraining shoulder as hereinafter described.

The steam cylinder 17 is supported above the pump 12 by the upright pillars 21, and 30 may be made to slide thereon for purposes of adjustment. This is accomplished by the crank 22 turning the shaft 23 which operates through a rack or pinion to depress and elevate the cylinder 17 as fully described in 35 said pending application. By admitting steam or the like from the pipe 24 to one side or the other of the piston within the cylinder 17, in any well known manner, the plunger 16 of the metal pump may be 40 pressed or raised at will. In the particular construction shown, as more fully described in my said pending application, suitable rotary valves, located within the valve box 25 are operated by means of a shaft 26. This 45 is accomplished by means of an arm 27 on said shaft connected by a pivoted link 28 to an arm 29 on the rock shaft 30. This last named shaft is operated from the main controlling handle hereinafter described, all as 50 fully explained in my said pending application.

The mold operating mechanism and main controlling means are supported upon stout brackets 31 fixed to the fire box 10 and may 55 be described generally as follows, omitting some details not relevant to the present improvement.

One side 32 of the separable mold is supported on the extremity of the rods 33, upon 60 which slides the support 34 carrying the second part of the mold shown at 35. The weight of the support 34 is partly carried by side pillars 36, having rollers 37 on their extremities, adapted to travel within slots 38 65 in the brackets 31. The sliding movement of

the support 34 on the rods 33 essential to opening and closing the mold is produced by connecting rods 39 and 40 one end of each of which is pivotally connected with the support 34 while their opposite ends are similarly connected with bell crank levers 41 and 42, which are made to move in unison by the link 43 connected, as shown, to both. 70

The parts so far mentioned are all supported by and project from one side of a 75 steam cylinder 44, having stiffening webs 45 attached to trunnions 46 turning in bearings 47 adapted to slide along the supporting rods 48, for purposes of adjustment. The cylinder contains a piston, not shown, by 80 movement up and down of which the bell crank levers 41 and 42 are made to rock to open or close the mold while moving it down upon the nozzle 15 by reason of the downward travel of the rollers 37 within the 85 inclined slot 38. This action together with the rack and pinion construction through which the piston in the cylinder 44 operates are set forth in detail in my said pending application. 90

Steam or the like is made to enter or leave one or the other end of the cylinder 44 by means of valves within the valve boxes 49, 50, which valves are operated by the rock shaft 51. The steam is supplied by the piping 52. A rocking arm 53 is so connected as to rock the valve shaft 51 at will, being preferably moved by a handle 54 forming part of a special form of main controller fully set forth in said pending application. 100 The same controller handle acts through the rock arm 55 to operate connections not here shown, whereby the shaft 30 is made to control the valve shaft 26. This, also, is fully shown in said pending application. 105

The mode of operation explained in my earlier application involved first, closing the mold and bringing it down into firm contact with the nozzle 15, by means of turning the steam into one end of the cylinder 44; second, forcing the molten metal into the mold by actuating the pump plunger 16, by means of steam admitted over the piston in the cylinder 17; third, when the mold had been filled, lifting the plunger 16 by exhausting 110 steam from the upper end of the cylinder 17 while admitting steam to the lower end thereof; and lastly reversing the action of the steam within the cylinder 44, so as to open the mold, to remove the article molded. 115 120

The present improvement involves changing this mode of operation to the extent of preventing movement of the plunger 16 during an interval of time sufficient to allow an accumulation of pressure in the upper end 125 of the cylinder 17, and then releasing the plunger, permitting it to shoot forward with a much more sudden movement than would otherwise be given it. This causes the molten metal to be thrown, so to speak, ex- 130

5 plosively into the mold so that it will become full and be subject to pressure before the cold walls thereof have had time to interfere with perfect action by any cooling of the metal.

10 In order to accomplish this end a variety of expedients may be resorted to and I have illustrated one of these in my drawings merely as an example of a variety of construction which would come within the scope of my invention.

15 Upon the rod or rods which connect the plunger 16 with the steam piston above it, I provide a restraining shoulder which may conveniently be the under surface of the socket 19. A bolt or bar 55^a slides within a guide piece 56, so that one extremity thereof may be slipped under the shoulder above mentioned, as shown in Fig. 2. The guide 20 piece 56 is shown as mounted upon a plate 56' which is preferably supported from the lower head of the steam cylinder 17 and is shown as connected thereto by means of bolts or rods 56. The outer extremity of 25 the bolt 55^a is connected to a link 55' which in turn is connected by a pin to a lever 57, whose other end bears a handle 58. This lever is pivoted at 59 to a bracket 60 which is preferably mounted on the side of the 30 fire box 10 in a manner to permit vertical adjustment, being finally secured by the bolts 61.

35 In operating the machine as thus constructed, the operator would stand in front of the same as it is shown in Fig. 1, between the two handles 54 and 58. After closing the mold down upon the nozzle 15 and admitting steam to the top of the cylinder 17, both by means of the handle 54, he would 40 pause sufficiently to allow the desired accumulation of pressure and would then push the handle 58 inward toward the fire box. This would withdraw the bolt 55^a, and allow the plunger to propel the metal suddenly 45 into the mold, as above described. The handle 58 would then be again used; first to lift the plunger 16 and then to open the mold. As soon as the plunger 16 is lifted, or at any time before renewed admission 50 of steam into the top of the cylinder 17, the operator should draw forward the handle 58, and slip the bolt 55^a under the restraining shoulder.

55 It is obvious that various modifications may be made in the construction shown in the drawings and above particularly described within the principle and scope of my invention.

I claim:

60 1. Means for applying the expansive power of an elastic fluid to a pump for molten metal in a casting apparatus, such means comprising a pump element to be moved by such elastic fluid, means for accumulating such fluid in potentially active

relation to said pump element, and means for restraining said pump element against movement during such accumulation and for suddenly releasing said pump element for movement while said pump element is subjected to such accumulated pressure of the elastic fluid. 70

2. Casting apparatus having, in combination, a positively acting pump for molten metal, pump-actuating means adapted to be 75 operated by the pressure of an elastic fluid and connected to the movable member of the pump, and manually controlled means for preventing the movement of and then suddenly releasing the movable member of 80 the pump.

3. Casting apparatus having, in combination, a pump for molten metal comprising a relatively movable cylinder and plunger, operating means for the pump comprising 85 a relatively movable cylinder and piston, the movable part of said operating means being connected to the movable part of the pump, means for supplying elastic fluid to the cylinder of the pump-operating means, 90 and a manually controlled catch device for locking said movable parts against movement and suddenly releasing them to permit their quick movement by the elastic fluid under accumulated pressure in the cylinder 95 of said pump-operating means.

4. Casting apparatus comprising a mold, a positively acting pump for forcing molten metal into the mold, means for accumulating a body of elastic fluid under high pressure in free relation with respect to the movable member of the pump, and means for restraining and finally suddenly releasing said member to produce a relatively quick propulsion of molten metal into the 105 mold. 100

5. In apparatus of the class described, a mold, a positively acting pump connected therewith by a suitable conduit, means for actuating the movable member of said 110 pump, means for accumulating a suitable driving pressure in operative relation with said actuating means, a restraining device for said pump, and means for rendering said restraining device nonoperative at will. 115

6. In apparatus of the class described, a mold, a positively acting pump connected therewith by a suitable conduit, means adapted to be driven by elastic fluid pressure for actuating the movable member of 120 said pump, a restraining device for the pump, and means for rendering said restraining device nonoperative at will.

7. In apparatus of the class described, a pump adapted to be operated by fluid pressure comprising a movable plunger, a bolt for restraining said plunger, and means for operating said bolt to confine or release the plunger at will. 125

8. In apparatus of the class described, a 130

plunger, a cylinder and piston adapted for operation by fluid pressure, a connection between said plunger and said piston, a restraining shoulder carried by said connection, and a bolt adapted to be slipped under said shoulder at will.

9. In apparatus of the class described, a plunger, a cylinder and piston adapted for operation by fluid pressure, a connection between said plunger and said piston comprising

ing two connecting rods united by a socket presenting a shoulder, and a bolt adapted to be slipped under said socket.

In testimony whereof I have affixed my signature.

GEOERGE WALDEMAR BUNRAY.
